DISPENSING CLOSURE FOR COLLAPSIBLE TUBES

Harold W. Beach, Abilene, Kans.

Application February 11, 1949, Serial No. 75,803

1 Claim. (Cl. 222—492)

1

This invention relates to new and useful improvements and structural refinements in dispensing closures, and the principal object of the invention is to provide a closure of this nature which is particularly well adapted for use in association with a collapsible tube containing tooth paste, shaving cream, etc., an important feature of the invention residing in the arrangement of the closure in such manner that it is automatically opened when the tube is being collapsed and is automatically closed as soon as collapsing pressure on the tube ceases to be exerted.

Some of the advantages of the invention lie in its simplicity of construction, in its adaptability to economical manufacture, and in its ability to protect the contents of the collapsible tube from harmful effects of the atmosphere.

With the above more important objects and features in view and such other objects and features as may become apparent as this specification proceeds, the invention consists essentially in the construction and arrangement of parts as shown in the accompanying drawings, in which:

Figure 1 is an elevational view of a collapsible tube showing the invention in situ thereon;

Figure 2 is a fragmentary cross-sectional view, taken substantially in the plane of the line 2—2 in Figure 1 and illustrating the invention in its closed position;

Figure 3 is a cross-sectional view, similar to that illustrated in Figure 2, but showing the invention in its open position; and

Figure 4 is a group perspective view of a plunger and a spring used in the invention.

Like characters of reference are employed to designate like parts in the specification and throughout the several views.

Referring now to the accompanying drawings in detail, the general reference character 10 designates a conventional collapsible tube provided with an externally screw-threaded outlet neck 12, the invention consisting of a dispensing closure designated generally by the reference character 14 which is intended to be positioned on the neck 12 in place of the conventional cap or top with which the collapsible tube is customarily provided.

The closure 14 embodies in its construction a cap-shaped body 16 formed with an axial bore 18, one end portion of this bore being screw threaded, as at 20, to receive the neck 12 of the tube 10, as will be clearly apparent.

A cylindrical closure member of plunger 22, equipped with a diametrically enlarged head 24, is slidable in the bore 18 from a retracted posi-

tion shown in Figures 1 and 2 to a projected position illustrated in Figure 3, the plunger constituting a closure for the bore when it is in its retracted position, as will be clearly apparent.

Needless to say, the enlarged head 24 of the plunger not only assists in closing the bore 18 when the plunger is retracted, but also functions as a stop to prevent the plunger from being retracted too far into the bore.

10 The plunger 22 is provided with a passage 26 which is in communication with the bore 18 and is open at diametrically opposite sides of the plunger, as is best shown in Figure 4. The passage 26 terminates in an outlet opening 28 which merely constitutes a continuation of one of the open sides of the passage 26, the opening 28 being disposed at one side of that portion of the plunger which is outside of the body 16 when the plunger is in its projected position as shown in Figure 3.

20 In other words, assuming the device to be in the closed position as shown in Figure 2, when pressure is exerted on the tube to collapse the same, the contents of the tube will flow outwardly through the neck 12 into the passage 18 of the body 16 and will exert pressure on the inside

25 end surface 30 of the plunger head 24, which pressure will expel the plunger 22 to its projected position, as shown in Figure 3, so that the contents of the tube 10 are discharged outwardly from the body 16 through the opening 28, as indicated at 32.

However, means are provided for returning the plunger 22 to its retracted position as soon as external pressure ceases to be exerted on the tube 10, these means involving the provision of a resilient wire rod or spring 34 which is best illustrated in the lower portion of Figure 4.

The spring 34 consists of two spaced side portions 36 which are connected together by an intermediate portion 38, the side portions 36 being formed with outward arcuations or detents 40, the extensions of which, in turn, constitute a pair of crossed end portions 42 terminating in arcuate loops or eyes 44.

45 The spring 34 is positioned in the bore 18 as indicated in Figures 2 and 3, having the intermediate portion 38 thereof extending transversely of the passage 26 of the plunger 22, while the arcuations 40 of this spring are seated in an annular groove 46 formed intermediate the length of the bore 18 for the purpose of preventing the spring 34 from shifting upwardly or outwardly from the bore. The crossed end portions 42 of the spring engage or bear against a cross piece 50 48 which extends transversely of the passage 26

in the plunger 22, whereby the plunger is urged in the direction of the arrow 50 in Figure 3 to its retracted position illustrated in Figure 2.

It should be explained that in Figure 4 the spring 34 is illustrated with the crossed end portions 42 extending downwardly, which position the end portions normally occupy before the spring is installed in the body 16. However, when the spring is installed in the body, the end portions 42 extend upwardly in crossed relation as shown, so that their resiliency is substantially increased. The spring 34 is, of course, sufficiently weak to allow the plunger 22 to be projected when external pressure is applied to the tube 10, but the spring is sufficiently strong to automatically return the plunger to its retracted position as soon as application of external pressure to the tube 10 is discontinued.

It is believed that the advantages and use of the invention will be clearly apparent from the foregoing disclosure, and accordingly, further description thereof at this point is deemed unnecessary.

Having described the invention, what is claimed as new is:

A dispensing closure comprising a vertically elongated body having an axial bore and an annular groove disposed intermediate the ends of said bore, said body being provided in said bore with a pair of diametrically opposite channels 30 extending longitudinally from the upper end of

the body to said groove, a hollow cylindrical closure member slidable in the upper portion of said bore and having open opposite sides at least one of which affords a lateral outlet passage when said member is projected upwardly from the bore, a cross-piece provided in the lower end of said member, and combined means for sliding said member downwardly and preventing upward withdrawal thereof from said bore, said means comprising a single length of resilient wire angulated to provide an inverted U-shaped body portion and a pair of crossed inwardly extending arms terminating in free extremities, said U-shaped body portion including a bight region extending transversely of said closure member above said cross-piece, and a pair of laterally projecting detents provided on said wire at the junctions of said U-shaped body portion with said arms, said detents being seated in said groove.
